UNITED STATES PATENT OFFICE.

JOHN F. FELDMAN, OF COLE CAMP, MISSOURI.

VEHICLE-SPOKE.

SPECIFICATION forming part of Letters Patent No. 416,328, dated December 3, 1889.

Application filed September 27, 1889. Serial No. 325,243. (No model.)

To all whom it may concern:

Be it known that I, JOHN F. FELDMAN, a citizen of the United States of America, residing at Cole Camp, in the county of Benton and State of Missouri, have invented certain new and useful Improvements in Vehicle-Spokes, of which the following is a specification, reference being had therein to the accompanying drawings.

10 My invention relates more particularly to the construction of the spokes of vehicle-wheels; and my object is to produce a more simple, cheap, and durable device for preventing the spokes and felly of a wheel from

15 wearing out than has hitherto been in vogue. With these ends in view my invention consists in the peculiar features of construction and combinations of parts, more fully described hereinafter, and pointed out in the

20 claims. Referring to the accompanying drawings, Figure 1 represents a side elevation of a wheel provided with my improved spokes; Fig. 2, a side elevation in cross-section of a portion 25 of the wheel, showing one spoke and part of the felly; and Figs. 3 and 4, detail views of the spoke proper and the thimble or sleeve for the same.

In the drawings, the reference-letter A indicates the spoke proper, which is made of wood and secured in the hub of the wheel in the usual manner. This spoke consists of a body portion *a*, which is of the usual diameter and is about two-thirds the length of the entire spoke, and a reduced portion or core *b*, extending from the shoulder *a'* to the outer end of the spoke, its outer extremity being provided with a screw-threaded perforation *b'*, for the purpose hereinafter explained. A metallic thimble or sleeve *B* is arranged to fit over this core *b*, and consists of a hollow cylindrical piece of metal having a closed outer head *c*, provided with a screw-threaded aperture *c'* in alignment with the perforation *b'* in the end of the core *b*. The inner end of this thimble fits snugly against the shoulder *a'* of the spoke proper, and near its outer extremity an annular shoulder or flange *d* is formed.

The felly *C* is provided with a perforation 50 *e*, of the same diameter as the thimble *B*, so that the outer end *f* of the same will fit within said perforation. This outer portion *f* has a length nearly equal to the width of the felly, and when fitted in the same the shoulder *d* 55 comes squarely against its inner surface.

The screw *g*, which secures the tire *G*, enters the screw-threaded aperture *c'* in the outer end of the thimble *B*, and also the perforation *b'* in the end of the spoke, so that 60 these parts are securely held together, and the necessity of having bolts or the like between the spokes is obviated.

A further advantage of my invention is that the bursting of the felly caused by the 65 swelling of the spoke is overcome by the use of my metallic sleeve, and many other advantages might be enumerated, which, however, will be apparent.

It is evident that slight changes which 70 might suggest themselves to one skilled in the art could be resorted to without departing from the spirit and scope of my invention; hence I do not limit myself to the precise construction herein shown. 75

Having thus described my invention, what I claim as new, and desire to secure by Letters Patent, is—

1. In a vehicle-wheel, the combination of a spoke proper having a reduced portion or 80 core, a metallic sleeve fitting over said core and in the felly of the wheel, and a tire secured to said core, substantially as described.

2. In a vehicle-wheel, the combination of a spoke proper having a reduced portion or 85 core, a metallic thimble or sleeve fitting over said core and arranged to enter the felly of the wheel, a shoulder on said thimble fitting against said felly, and a tire secured to said thimble and said core, substantially as de- 90 scribed.

3. In a vehicle-wheel, the combination of a spoke proper having a reduced portion or core provided with an aperture in its outer end, a metallic thimble fitting over said core 95 and having a perforation in its head registering with the aperture in said core, a felly having a perforation in which the outer end

of said thimble fits, an annular shoulder on
said thimble fitting against the inner surface
of said felly, and a tire secured to the wheel
by a screw or its equivalent, which enters the
5 perforation in the thimble-head, and also that
in the core, in the manner and for the pur-
pose described.

In testimony whereof I affix my signature in
presence of two witnesses.

JOHN F. FELDMAN.
